UNITED STATES PATENT OFFICE.

IRA E. CORNELL, OF AKRON, OHIO.

OVERCHECK-HOOK.

1,139,166.

Specification of Letters Patent. Patented May 11, 1915.

Application filed April 7, 1914. Serial No. 830,233.

To all whom it may concern:

Be it known that I, IRA E. CORNELL, a citizen of the United States, residing at Akron, in the county of Summit and State 5 of Ohio, have invented new and useful Improvements in Overcheck-Hooks, of which the following is a specification.

This invention is an improved overcheck hook, the object of the invention being to 10 provide an improved device of this kind which may be made to match any shape or form of terret and which is adapted to secure an overcheck rein so that the latter cannot become casually released but it may be 15 readily detached or adjusted when desired, the object of the invention being to provide an improved device of this character which is extremely cheap and simple, is strong and durable, and is not likely to get out of order.

20 The invention consists in the construction, combination and arrangement of devices hereinafter described and claimed.

In the accompanying drawings:—Figure 1 is a front elevation of an overcheck hook 25 constructed in accordance with my invention. Fig. 2 is a rear elevation of the same. Fig. 3 is a vertical central sectional view of the same showing the tongue in engaged position in full lines and in disengaged position 30 in dotted lines.

In the embodiment of my invention I provide a base 1 which has a bolt stem 2 on its under side to adapt the device to be readily secured to a harness saddle. The 35 base is formed with a pair of upwardly extending fork arms 3 which are united at their lower ends as at 4. The portion 4 between the lower ends of the fork arms is formed with a recess 5 in its rear side. I 40 also provide a tongue 6 for engagement with any of the adjusting openings in an overcheck line, this tongue being provided with an enlarged free end 7 adapted to fit in the recess 5 and the tongue being provided at 45 its outer end with a cross arm 8 the ends of which are pivotally mounted in bearing openings near the upper ends of the fork arms. Thereby the tongue is adapted to be turned upwardly to release position or 50 to be turned downwardly to engaged posi-

tion, with its lower or outer end fitted in the recess 5. It will be understood that since the recess is on the rear side of the device, the stress on the check line will hold the tongue in vertical closed position. In order to release the check line it is only necessary to raise the tongue rearwardly, when the check line can then be readily slipped therefrom.

The enlarged end 7 of the tongue holds 60 the overcheck line on the tongue and causes the weight of the check line to keep the tongue in lowered, vertical position, even when the check line is not under tension, so that there is no tendency of the check 65 line to become detached from the tongue and moreover as will be observed, upon reference to Fig. 3, the length of the enlarged portion of the tongue corresponds with the depth of the recess 5 so that the overcheck 70 line also bears directly on the base and offers frictional resistance which contributes in keeping the check line engaged with the tongue.

My improved overcheck hook may be 75 made to match any shape or form of terret and in practice will be put up in sets each containing two terrets and one of my overcheck hooks.

Having thus described my invention, I 80 claim:—

The herein described overcheck hook comprising a base having a bolt stem on its under side and also having a pair of upwardly extending fork arms on its upper side united 85 at their lower ends and provided in the position between their lower ends with a recess which is open at the rear side, in combination with a tongue provided at its free end with an enlarged portion adapted to engage 90 in and correspond in length with the recess, the said tongue being provided at the opposite end with cross arms pivotally mounted in said fork arms.

In testimony whereof I affix my signature 95 in presence of two witnesses.

IRA E. CORNELL.
